UNITED STATES PATENT OFFICE.

ALBERT E. CHURCH, OF NEW BRITAIN, CONNECTICUT.

BENCH VISE.

Application filed December 9, 1921. Serial No. 521,217.

To all whom it may concern:

Be it known that I, ALBERT E. CHURCH, a citizen of the United States, residing at New Britain, in the county of Hartford and State 5 of Connecticut, have invented certain new and useful Improvements in Bench Vises; and I do declare the following to be a full, clear, and exact description of the invention, such as will enable others skilled in the 10 art to which it appertains, to make and use the same.

My invention relates to improvements in bench vises and has for its principal object, the provision of a vise which may be 15 quickly and easily converted for operation totally by hand, or to combine hand-operated and power operated actuating means for the movable jaw. By this arrangement, the vise may be shipped from the factory as 20 a hand vise only if the purchaser so requires, or if the vise is ordered with power-operated actuating means, this means may be quickly applied before shipment. Furthermore, a 25 purchaser is enabled to obtain the vise with hand-operating means only and at a later date to purchase the power-operated actuating means and install the latter himself with ease.

With the foregoing in view, the invention 30 resides in the novel subject matter hereinafter described and claimed, the descriptive matter being supplemented by the accompanying drawings:

Figure 1 is a side elevation of a vise constructed in accordance with my invention, 35 showing the power-operated jaw actuating means applied.

Figure 2 is a top plan view of the construction shown in Fig. 1.

Figure 3 is a central longitudinal sectional view as indicated by line 3—3 of Fig. 2.

Figure 4 is a vertical transverse section on line 4—4 of Fig. 3.

Figure 5 is a detail horizontal sectional view as indicated by line 5—5 of Fig. 3.

Figure 6 is a detail sectional view showing a different form of screw-engaging nut which is employed when the vise is to be 50 furnished for operation by hand.

Figure 7 is a side elevation of the nut shown in Fig. 6.

Figure 8 is a side elevation of the nut shown in the other figures.

55 In the principal showing of my invention, I have illustrated the vise as embodying both

hand-operated and power-operated jaw actuating means, but it will be understood from the following description that the power-operated means may or may not be 60 furnished with the device when sold.

The numeral 1 designates a suitable body carrying the usual fixed jaw 2, said body being provided with outstanding flanges or other suitable means 3 whereby it may be 65 secured upon a bench or other suitable support. The body 1 is internally recessed as indicated at 4 and the recess opens through the rear end of the body as clearly shown in Fig. 3, but the front end portion of said 70 body is solid with the exception of a horizontal screw-receiving opening 5 and a pair of flat-sided openings 6 disposed above and below said opening 5. The openings 6 slidably receive a pair of flat-sided guide bars 7 75 which are rigidly secured to a movable jaw 8, and an operating screw 9 which is swiveled in said jaw, passes through the opening 5 but has no threaded engagement with the wall thereof.

The rear end portion of the screw 9 is threaded in a horizontally elongated tubular nut 10 whose front end is slidably received in a recess 11 in the body 1, said recess being preferably formed by counter-boring the 85 rear end of the opening 5 as shown in Fig. 3. The nut 10 is held against rotation by means of a nut-holding device which is preferably in the form of a screw 12 threaded transversely through one side of the body 1 90 and projectable at its inner end into the recess 11, the nut 10 being provided with a longitudinal groove or keyway 13 receiving said inner end of the screw 12 as shown most clearly in Figs. 3 and 5. This construction holds the nut 10 against rotation 95 but permits slight sliding movement of said nut for a purpose to be hereinafter set forth.

The rear end of the nut 10 is provided with a lug 14 or other suitable means where- 100 by mechanical means may be connected with said nut for bodily shifting the same and the screw 9 to operate the jaw 8 by power. In the present showing, a piston rod 15 is connected by a removable pin 16 with the 105 lug 14 and said piston rod is equipped with a suitable piston 17 within a fluid pressure cylinder 18. This cylinder is provided with means for quickly attaching it to or detaching it from the body 1 and as here 110 shown, this means consists of a forwardly extending flange 19 which is of arch shape

as shown in Fig. 4 to rest over the rear end portion 20 of the body 1, which portion is also of arched contour. The inner side of the flange 19 is preferably formed with a shoulder 21 abutting the rear end of the body 1 and screws or the like 22 are used to secure said flange to the body, whereby to rigidly mount the cylinder 18.

Any suitable spring means, such as a plurality of coiled springs 23, are employed for shifting the piston 17 and associated parts to a forward position, while air or other suitable pressure may be conducted to the front end of the cylinder 18 through a pipe 24, to force the piston rearwardly and thereby move the jaw 8 to gripping position. Any suitable valve 26 may be employed for controlling the passage of air or other fluid pressure to the pipe 24 from a pressure supply line 27 and I prefer to detachably mount this valve upon the body 1, for instance, by means of screws 28.

From the construction so far described, it will be seen that by means of the screw 9, the jaws 2 and 8 may be set different distances from each other according to the work to be handled and after so setting said jaws, they may be closed by fluid pressure but since the springs 23 or their equivalent are used to open the vise, a great economy is effected in the amount of compressed air or the like which is used. It is of course understood that the valve 26 is of such form as to either admit pressure to the cylinder 18 or to permit this pressure to exhaust, but the construction of this valve need not be disclosed as any of the well known valves on the market may be employed for this purpose.

When the vise is to be sold without the cylinder 18 and associated parts, so that the device may be operated entirely by hand, I prefer to substitute a much shorter nut 10^a for the nut 10 (see Figs. 6 and 7). This nut is received in the recess 11 and is held therein by the screw 12 whose inner end is engaged with a socket 13^a in one side of the nut.

If a purchaser wishes one of the vises to be operated entirely by hand, it is furnished without the cylinder 18, the nut 10 and associated parts, and one of the shorter nuts 11 is used. If a vise is required however which can be operated both by hand and by power, the device is furnished in the form shown in Figs. 1, 2 and 3. Furthermore, it will be seen that any one initially purchasing the vise without the pressure-operated actuating means, may at a later date purchase such operating means and install the same with ease. Thus, the varying requirements of the trade may be effectively met without manufacturing first, a vise operated totally by hand; second, a vise

operated totally by power; and third, a vise to be operated by both hand and power.

In view of the fact that excellent results are now being obtained from the general construction herein described and illustrated, this construction is preferably followed, but it is to be understood that within the scope of the invention as claimed, numerous changes may be made.

I claim:

1. A bench vise comprising a body having a fixed jaw at its front end, a movable jaw in front of said fixed jaw having guiding means engaged with said body, a screw swiveled in said jaw and having a handle at the front side thereof, said screw extending slidably and rotatably into said body, a nut into which said screw is threaded, said nut being slidably mounted in said body, a fluid pressure cylinder carried by the rear end of said body in axial alignment with said nut, and a piston in said cylinder having connection with said nut for sliding the same to operate the vise by power.

2. A bench vise comprising a fixed-jaw carrying body having a recess adapted to non-rotatably receive either of two forms of nuts and to slidably receive one of said nuts, said body having a shoulder at one end of said recess adapted to hold the other form of nut against movement in one direction, said body being adapted for connecting a piston containing cylinder to its rear portion in axial alignment with said recess, whereby the piston may be connected to said one nut for sliding the same, a movable jaw cooperable with the fixed jaw of said body, and a hand screw swiveled in said movable jaw and adapted for engagement with either nut.

3. A bench vise comprising a body having a fixed jaw, said body having a recess to fixedly receive one form of nut or to slidably receive another form of nut, a nut-holding device carried by said body with its inner ends projectable into said recess for reception in a keyway of the sliding nut or a socket of the other nut, and a movable jaw having a hand-operated screw for operative engagement with either nut, said body being adapted for the attachment of mechanical means thereto for sliding the second mentioned nut when the latter is used.

4. A tubular nut for sliding reception in a vise body, said nut having a longitudinal groove in one side to receive a nut-holding device and being additionally provided with an apertured lug on one end by means of which mechanical nut-operating means may be attached.

In testimony whereof I have hereunto set my hand.

ALBERT E. CHURCH.
